Inventor
William S. Luckett,

By Wm. L. Edmonson
Atty.

UNITED STATES PATENT OFFICE.

WILLIAM S. LUCKETT, OF SPRINGFIELD TOWNSHIP, MONTGOMERY COUNTY, PENNSYLVANIA.

GOLF KIT.

Application filed March 8, 1922. Serial No. 542,046.

To all whom it may concern:

Be it known that I, WILLIAM S. LUCKETT, a citizen of the United States, residing at Springfield Township, in the county of 5 Montgomery and State of Pennsylvania, have invented certain new and useful Improvements in Golf Kits, of which the following is a specification.

This invention has reference generally to 10 improvements in special article carriers and more particularly relates to an improved golf kit and supporting stick therefor.

It is the principal aim and object of this invention to provide a kit having separate 15 open compartments for the reception of the shank portions of golf sticks, the compartments being preferably arranged in the body of the kit so that the sticks when supported therein will be inclined toward each 20 other and will tend to contact with each other at a point remote from the kit but in substantial alignment with the longitudinal axis thereof, to facilitate carrying the kit, which is, of course, also provided with a 25 hand grip and shoulder engaging strap as well as ball receiving means.

As an additional and equally important object the invention contemplates in combination with the kit the provision of an improved supporting stick adapted to be carried 30 in the hand or within the kit when not in use, but being removable therefrom for engagement with the ground, means being provided thereon for receiving the hand 35 grip or other engaging parts of the kit to support the kit and the golf sticks therein in a convenient position for the golfer or player, especially one who is without the assistance of a caddy.

More specific objects of the invention reside in the provision of a golf kit of novel construction with a supporting stick having a removable ground engaging and supporting prong, which when the stick 45 is not in use may be accommodated in the upper grip receiving portion to facilitate carrying of the same in the kit or in the hand as a cane.

Among the other aims and objects of the 50 invention may be recited the provision of an article of the above mentioned character with a view to compactness and wherein the number of parts are few, the construction

simple, the cost of production low and the efficiency high.

Further objects as well as the nature, characteristic features and scope of the invention will be more readily apparent from the following description taken in connection with the accompanying drawings and pointed out in the claims forming a part of this specification.

The invention is clearly illustrated in the accompanying drawings, in which:—

Figure 1 is a side elevation of the invention showing the kit, with the sticks therein, suspended from the support,

Figure 2 is a top plan view of the kit,

Figure 3 is a section taken on the line 3—3 of Figure 2, and,

Figure 4 is an enlarged fragmentary elevational detail partly in section of the supporting stick.

Similar characters of reference are employed in all of the above described views 75 to indicate corresponding parts.

Referring now, more particularly, to the accompanying drawings, there is provided the novel golf kit generally indicated by the numeral 1 adapted for association with the improved supporting stick indicated in its 80 entirety by the numeral 2.

The kit may consist of a substantially cylindrical open body 3 having a plurality of golf stick receiving compartments 4 arranged therein. The compartments may comprise a plurality of tubes or the like which may be formed of any of several materials including light metal, leather, canvas or hardened or soft rubber of sufficient rigidity to prevent collapsing thereof. The tubes may also be fitted with outer coverings 85 to facilitate the securing of the same to each other and to the upper and lower edges of the body of the kit in any suitable manner such as by stitching 6, both the coverings 90 and the body 1 of the kit being formed of relatively stiff material such as canvas. It is preferred that the compartments or tubes 4 be arranged in circular series with one 100 positioned in the center and those in circular series being so secured to each other and to the body as to be inclined toward the lower end of the kit so that when the golf sticks 7 are arranged therein, the driving ends or heads will engage the upper edges of the

tubes while the handle portions will be inclined toward each other to contact near their extreme outer ends at a point substantially in alignment with the axis of the center tube, this arrangement greatly facilitating the carrying of the kit with the clubs arranged therein. A ball receiving pocket 8 is provided for the kit and may be secured to the outer surface of the body thereof. To facilitate carrying and supporting of the kit a hand grip 9 and a shoulder engaging strap 10 may be connected thereto.

With a view toward providing the improved supporting stick the lower end of the shank 11 may be fitted with a removable ground penetrating prong 12 having a disk-like ground engaging element 13 thereon, being adjustable upward and downward in accordance with the firmness of the ground to be engaged, which facilitates supporting, while the upper end of the shank may carry a kit receiving and supporting member 14 having desirably an attaching portion 15 and opposed upright portions 16 carried thereby, the portion 15 being also formed with a socket 17 for removably receiving, at times, the pointed end of the prong.

It is apparent that when not in use the prong may be received in the socket and the stick inserted in the center compartment of the kit. On the other hand when it is desired to use the same the stick may be removed from the kit, the prong connected to the outer end of the shank and jabbed into the ground whereupon the kit may be supported thereby when the hand grip is engaged with the receiving portion therefor.

Of course, it will be understood that various changes might be made in size, shape and material, and yet be within the scope of my invention.

It is believed in view of the foregoing description that a further detailed description of the invention is entirely unnecessary.

Likewise, it is believed that the advantages, 45 both constructional and commercial, of the invention will be readily apparent.

Having thus fully described the invention what is claimed as new and desired to be secured by Letters Patent is:—

1. A golf kit including a substantially cylindrical open ended body of flexible material and possessing sufficient rigidity to maintain its cylindrical form, a plurality of open ended stick receiving tubes therein and of a material similar to the material of the body, one of the tubes being arranged in the center and the other tubes in cylindrical series and intimately connected with the center tube through the length of the body and slightly inclined toward the lower end of the body, a hand grip carried with the body and a shoulder engaging strap carried with the body.

2. The combination, of a kit having a plurality of open ended stick receiving compartments arranged in circular series therein and having one compartment positioned centrally of the series, and a hand grip on the kit, of a supporting stick adapted to be carried in one of the compartments of the kit when not in use, a detachable ground engaging and supporting prong having a flange associated with one end of the stick for facilitating the supporting of the stick but removable therefrom to permit of the stick being inserted in one of the compartments, and a kit receiving member engaged with the opposite end of the shank and provided with a socket adapted to receive the prong when detached.

In testimony whereof I affix my signature in the presence of two witnesses.

WILLIAM S. LUCKETT.
